UNITED STATES PATENT OFFICE.

GEORGE W. LEWIS, OF GRINNELL, IOWA.

GEARING DEVICE FOR WASHING-MACHINES AND WRINGERS.

1,116,087.

Specification of Letters Patent.

Patented Nov. 3, 1914.

Original application filed February 14, 1910, Serial No. 543,883. Divided and this application filed December 8, 1913. Serial No. 305,460.

To all whom it may concern:

Be it known that I, GEORGE W. LEWIS, a citizen of the United States, and resident of Grinnell, in the county of Poweshiek and State of Iowa, have invented a certain new and useful Gearing Device for Washing-Machines and Wringers, of which the following is a specification.

The object of my invention is to provide a gearing device of simple, durable and inexpensive construction for imparting motion from one shaft to another and for quickly and easily reversing the direction of the rotation of the driven shaft for throwing it out of gear with relation to the first shaft.

A further object is to provide such a mechanism and to provide means whereby said mechanism may be operated from a foot pedal for throwing the two shafts out of gear with each other or rotating the driven shaft in either direction.

Still a further object is to provide in such a device a gear casing, suitably constructed for containing the reversing gears.

My invention consists in certain details, in the construction, combination and arrangement of the various parts of the device, whereby the objects contemplated are attained, as hereinafter more fully set forth, pointed out in my claims and illustrated in the accompanying drawings, in which—

Figure 1 shows a side elevation of a washing machine and wringer equipped with a gearing device embodying my invention. Fig. 2 shows a detail view, partly in section, of a portion of the controlling mechanism. Fig. 3 shows a top or plan view of a washing machine and wringer and the reversing gears, the upper portion of the gear casing being removed. Fig. 4 shows a plan view of the cam slotted bar for shifting the gears. Fig. 5 shows a vertical, sectional view through the gear casing and the reverse mechanism, and Fig. 6 shows a horizontal, sectional view, through the same.

It is my purpose to devise a gearing of the class mentioned, particularly designed for use with washing machines and wringers. I have, therefore, in the accompanying drawings used the reference numeral 10 to indicate a tub of a washing machine which is supported upon the legs 11 and which carries a wringer indicated generally by the reference numeral 12. The tub may be pro-

vided with a hinged cover 13 and with suitable mechanism 14 for operating a dolly. Mounted upon the solid portion of the tub cover is a horizontal shaft 15, upon which is a fly wheel or belt pulley 16. The shaft 17 of one of the wringer rolls extends beyond the frame of the wringer and the shafts 17 and 15 preferably lie in substantially the same horizontal planes with the end of the end of the shaft 15 near the shaft 17.

Suitably mounted is a gear casing, comprising a lower half 18 and an upper half 19. The lower half of the gear casing is mounted on a suitable support and the upper half thereof is detachable. The lower gear casing member 18 is provided with a bearing 21 for the shaft 15 which extends into the casing.

Mounted upon the shaft 15, within the gear casing and near the end of the shaft 15, is a beveled gear 22. Slidably but non-rotatably mounted upon the shaft 17, within the gear casing, is a sleeve 23, having formed on its ends beveled gears 24 and 25, designed to respectively mesh with the gear 22 in different positions of the sliding movement of the sleeve 23 and in certain positions of said sleeve to be held out of mesh with the gear 22. For sliding the sleeve 23 upon the shaft 17, I have provided the following means: The cam plate 26 is arranged to slide vertically with the portion 18 of the gear casing with its side edges substantially in engagement with the gears 24 and 25, as shown in Fig. 6. Close to the sleeve 23 in the plate 26 is a cam groove 27 in which the end of the shaft 15 is received. This cam groove is so shaped and arranged that when the plate 26 is at the upper limit of its movement, it will be forced toward the wringer and the outer gear 25 will be moved to position in mesh with the gear 22 and the wringer will be operated in one direction. When the plate 26 is moved downwardly until the shaft 17 is at the central portion of the cam slot 27, then the parts will be in the position shown in Fig. 6 and both the gears 24 and 25 will be out of mesh with the gear 22. When the plate 26 is moved to the upper position of its movement, the shaft 15 will force the plate laterally away from the wringer, thereby moving the sleeve 23 away from the wringer and moving the gear 24 into mesh with the

gear 22, thereby causing the wringer to be operated in a direction opposite from that first described.

The mechanism for operating the cam plate 26 by foot pedal will now be described.

Fixed to the lower end of the plate 26 is a rod 28 extending downwardly and pivoted to one end of the bell crank lever 29, which is centrally fulcrumed to a bracket 30 secured to the tub 10. One arm of the bell crank lever 29 extends downwardly from the fulcrumed bracket 30 and fixed on its lower end is a foot pedal 31 which travels in a metal guide loop 32, formed in one side of which are notches 33, 34 and 35, designed to engage said foot pedal and hold it against upward movement when so engaged.

For normally inserting the yielding power for drawing the lever 29 toward the position where the foot pedal 31 will be at its highest point of movement, I have secured to one arm of the lever 29 and to one of the legs 11 a coil spring 36. The lever 27 and foot pedal 31 are so constructed and mounted that the foot pedal may be swung slightly laterally for causing it to enter or clear the notches 33, 34 and 35.

It will readily be seen that the spring 36 normally holds the foot pedal at the upward position of its movement. By moving the foot pedal, it will engage the notch 34 and the shaft 17 may be thrown out of gear.

The advantages of my improved mechanism may be partially seen from the foregoing description. The means for shifting the sleeve 23 are simple and inexpensive and are not likely to get out of order. The operation of the plate with the cam slot is accurate and true and the use of such plate makes possible the use of the foot pedal for controlling the reversing mechanism.

This application has been divided out of my now pending application for United States Letters Patent on a gearing for washing machines filed on February 14, 1910, Serial No. 543,883.

It will be understood that some changes may be made in the details of the construction of my device without departing from its essential features and it is my purpose to cover by this application any such changes which may be included within the scope of the appended claims.

I claim as my invention:

1. In a gearing device of the class described, the combination of two horizontally arranged shafts, means for connecting said shafts, comprising a sleeve slidingly and non-

rotatably mounted on one of said shafts, two beveled pinions on said sleeve, a beveled pinion on the other shaft in position to mesh with either one of said pinions, means for shifting said sleeve comprising a vertically movable plate having a cam groove therein designed to receive the end of one of the horizontally arranged shafts, the sides of said plate being designed to engage said beveled pinions on the sleeve, and means for moving said plate vertically.

2. In a gearing device of the class described, the combination of a power shaft, a horizontally arranged shaft, a sleeve slidingly and non-rotatably mounted thereon, two beveled pinions on said sleeve, a beveled pinion of the power shaft to stand between the beveled pinions on the sleeve and to mesh with either one of said pinions on the sleeve, means for shifting said sleeve, said means comprising a vertically movable plate having a cam groove therein designed to receive the end of the power shaft, the sides of said plate being designed to engage said beveled pinions on the sleeve, means for moving said plate vertically, said means comprising a lever having a treadle at one end, a link connecting said lever with said slide plate, and means for securing the treadle in different positions of its adjustment.

3. In a gearing device of the class described, the combination of a power shaft, a horizontally arranged shaft, a sleeve slidingly and non-rotatably mounted thereon, two beveled pinions on said sleeve, a beveled pinion on the power shaft to stand between the beveled pinions on the sleeve and to mesh with either one of said pinions on the sleeve, means for shifting said sleeve, said means comprising a vertically movable plate, a cam groove therein designed to receive the end of the power shaft, the sides of said plate being designed to engage said beveled pinions on the sleeve, means for moving said plate vertically, said means comprising a lever having a treadle at one end, a link connecting said lever with the said slide plate, means for securing the treadle in different positions of its adjustment, and a spring for normally elevating the treadle.

Des Moines, Iowa, July 31, 1913.

GEORGE W. LEWIS.
